Primary Examiner — Jennifer L Rempfer*Assistant Examiner* — Bethany Louise Mallino(74) *Attorney, Agent, or Firm* — Cabilly & Co.(57) **CLAIM**

The ornamental design for a door hanger organizer, as shown and described.

DESCRIPTION

FIG. 1 is a front view showing the new design of the door hanger organizer having four pockets and four hook holes; FIG. 2 is a left view thereof showing four sleeves configured on the back side of the door hanger organizer; FIG. 3 is a right view thereof;

FIG. 4 is a top view thereof;

FIG. 5 is a bottom view thereof;

FIG. 6 is a back view thereof;

FIG. 7 is a perspective view of the door hanger organizer retained on a door by hooks configured in the four hook holes; and,

FIG. 8 is a perspective view of the door hanger organizer shown in FIG. 7 having toys configured in the top three pockets.

The equal-length broken lines in the drawings of a door, hooks, and articles retained within the pockets of the door hanger organizer show environment of use and form no part of the claimed design.

1 Claim, 3 Drawing Sheets(56)
